(57) **CLAIM**

The ornamental design for a vehicle mount, as shown and described.

DESCRIPTION

FIG. 1 is a front-top-left perspective view of a vehicle mount showing a first embodiment of our new design;

FIG. 2 is a left-side view thereof;

FIG. 3 is a right-side view thereof;

FIG. 4 is a front view thereof;

FIG. 5 is a back view thereof;

FIG. 6 is a top view thereof; and

FIG. 7 is a bottom view thereof; and

FIG. 8 is a front-top-left perspective view of a vehicle mount showing a second embodiment of our new design;

FIG. 9 is a left-side view thereof;

FIG. 10 is a right-side view thereof;

FIG. 11 is a front view thereof;

FIG. 12 is a back view thereof;

FIG. 13 is a top view thereof; and,

FIG. 14 is a bottom view thereof.

The broken lines shown in the drawings depict portions of the vehicle mount that form no part of the claimed design.
